[57] **ABSTRACT**

A feed mixture of tetrafluoroethylene and a minor proportion of carbon dioxide is fed to a pyrolysis furnace operating at about atmospheric pressure and a temperature of 700° to 900°C., and a conversion of 20 to 80 percent by weight, to a yeild of at least 80 percent by weight of hexafluoropropylene and a mixture of carbon dioxide and unreacted tetrafluoroethylene which is distilled from the hexafluoropropylene. The distillate mixture can be recycled to the pyrolysis furnace.

6 Claims, No Drawings

PROCESS FOR PYROLYZING
TETRAFLUOROETHYLENE TO
HEXAFLUOROPROPYLENE

This invention relates to pyrolysis of tetrafluoroethylene to hexafluoropropylene.

U.S. Pat. No. 2,551,573 to Downing et al. discloses the pyrolysis of CHClF_2 to tetrafluoroethylene and higher boiling fluorocarbon products. U.S. Pat. No. 2,758,138 to Nelson discloses the pyrolysis of tetrafluoroethylene to hexafluoropropylene at various specific conditions involving low partial pressures, i.e., 25 to 200 mm. of Hg, of the tetrafluoroethylene feed. A process for pyrolyzing tetrafluoroethylene to hexafluoropropylene at higher pressures, viz., 0.2 to 65 psia, is disclosed in U.S. Pat. No. 2,970,176 to Ten Eyck et al., wherein the tetrafluoroethylene feed contains at least 5 weight percent of higher boiling fluorocarbon compounds which contribute to the formation of hexafluoropropylene. A more economical process was developed later in which CHClF_2 is pyrolyzed to both tetrafluoroethylene and hexafluoropropylene by conducting the pyrolysis within a specific conversion range of 86 to 94 percent as described in U.S. Pat. No. 3,306,940 to Halliwell.

The present invention provides a pyrolysis process for making hexafluoropropylene which is economically advantageous over all the foregoing described processes. The process involves pyrolyzing a feed of tetrafluoroethylene (TFE) and a minor proportion of carbon dioxide in a reaction zone at a temperature of 700° to 900°C., and a pressure of 0.75 to 2.0 atmospheres absolute, and a minimum partial pressure of TFE of 360 mm. of Hg absolute, to a conversion of TFE at least of 20 percent by weight, separating the unpyrolyzed TFE and the carbon dioxide from the hexafluoropropylene (HFP) and other pyrolysis products produced, and, if desired, recycling the separated TFE and carbon dioxide to the reaction zone while adding make-up TFE to maintain a substantially constant proportion of TFE in the feed to the reaction zone. The process has been operated economically at conversions of TFE up to about 80 percent. The major pyrolysis product, i.e., greater than 50 percent by weight of the pyrolysis products, is HFP. Yields of greater than 80 percent by weight and as high as 90 percent by weight of TFE to HFP, the desired product, can be obtained by this process. When the unpyrolyzed TFE and carbon dioxide are recycled to the reaction zone, then steps to isolate the carbon dioxide from the TFE are unnecessary.

A major problem involved in pyrolyzing TFE is its tendency to disproportionate to carbon tetrafluoride and carbon according to the reaction

which represents both a yield loss of expensive chemical and causes plugging of the reaction apparatus. This disproportionation is an exothermic reaction so once it begins, it tends to be a runaway reaction. The invention of the aforementioned Nelson patent attempted to avoid this problem by operating at very low pressures, i.e., less than 200 mm. of Hg absolute. This low pressure of operation was obtained by continuously evacuating the pyrolysis furnace and feeding the TFE to the furnace, which, by itself, determined the pressure in the furnace. One disadvantage of this vacuum operation was the danger of leakage of air into the pyrolysis sys-

tem from the surrounding atmosphere which would result in oxidation of TFE and could give an explosive mixture of air in TFE. Another disadvantage was the need for using larger equipment for the same throughput achieved at higher pressure operations, such as disclosed in the Downing et al. patent.

The invention of the Ten Eyck et al. patent found that TFE could be pyrolyzed to HFP at higher, more conveniently obtainable pressures such as atmospheric pressure, but this required the presence of at least 5 percent of pyrolyzable fluorocarbon materials having a boiling point higher than HFP which were normally provided by recycling the higher boiling pyrolyzate, which had the disadvantage of repeated handling of 15 highly toxic materials rather than leading to quick waste disposal thereof.

The present invention also operates at the more favored pressure condition of around atmospheric pressure but without requiring the presence of the high-boiling fluorocarbon compounds and the attendant toxicity problem and yet avoiding the disproportionate problem.

The process of the present invention is most conveniently conducted preferably at atmospheric pressure 25 by passing a mixture of the TFE and carbon dioxide through a heated tube, called a pyrolysis furnace, with the heated portion of the tube being the reaction or pyrolysis zone. The presence of the carbon dioxide in the pyrolysis furnace during the pyrolysis of TFE in the 30 present invention prevents the undesirable disproportionation of the TFE despite the partial pressure of TFE being substantially higher than that disclosed by Nelson.

With respect to the proportions of TFE and carbon 35 dioxide in the feed to the reaction zone (pyrolysis furnace), there is always a greater weight of TFE present than carbon dioxide, and thus the latter is present as a minor proportion (weight basis) of the feed. Typically the proportion of TFE to carbon dioxide in the feed will 40 be from 1:1 to 25:1 on a weight basis. At proportions of TFE/ CO_2 of greater than 25:1, it is feared that long-term repression of the disproportionation reaction will not occur. The feed mixture to the reaction zone advantageously contains at least 40 percent by weight 45 (total feed basis) of carbon dioxide to render the mixture nonflammable in case of leakage to the atmosphere. Preferably, the partial pressure of TFE in the feed mixture is at least 450 mm. of Hg absolute.

Immediately succeeding the pyrolysis zone of the furnace, gaseous hydrogen chloride or hydrogen fluoride is preferably injected into the pyrolysis mixture as described in U.S. Pat. No. 3,578,721 to Couture et al., in order to prevent polymerization of unreacted TFE 50 which would eventually cause plugging of the recovery system.

The next step in the process is to recover the unreacted TFE and carbon dioxide as a mixture from the rest of the pyrolysis mixture by techniques well known in the art, such as distillation. The boiling point of the TFE is -76.8°C. and the sublimation point of carbon dioxide is -78°C. which enables these compounds to be 55 separated from the HFP (b.p. -29°C) and higher boiling fluorocarbon pyrolysis products in a single distillation operation and recovered as a mixture. The distillation is conducted under pressure, such as 17.5 kg/cm² (gauge), to raise the boiling point of the distillate to a convenient temperature of operation, which tempera-

ture is above the temperature at which solid CO_2 could exist in the distillation system. If HCl is added to the pyrolyzate, as described above, it will distill with the TFE as an azeotrope therewith. If the additive is HF , it will not distill with the TFE but will remain with the HFP and other high-boiling pyrolysis products. When the HCl is distilled with the TFE and carbon dioxide, the resultant gaseous mixture can be passed through a conventional water-scrubber to remove the HCl to prevent the HCl from being recycled to the pyrolysis furnace with the recycled carbon dioxide and TFE .

If the HCl were to be recycled to the pyrolysis furnace there would be a yield loss because HCl would be reactive with TFE and with the difluorocarbene rad-

a mixture to the Inconel tube via calibrated rotameters. Hydrogen chloride was injected into the exit zone of the pyrolysis tube where the temperature was about 500°C. to inhibit polymerization of unreacted TFE in the collection system. The Inconel tube was heated to the desired reaction temperature with a carbon dioxide purge and then TFE was added to the feed stream to the tube to obtain a mixture having the desired TFE/CO_2 ratio. The pyrolysis was conducted at about atmospheric pressure. Samples of the exit gas from the tube were scrubbed in water to remove HCl and analyzed by gas chromatography to establish yields and conversions. Further details of these experiments and the results are shown in the following Table:

Exam- ple	Temp. °C.	Contact time-sec.	HCl feed rate ml/min.	TFE/CO_2 wt.ratio	TFE Conversion %	Yield to HFP %
1	809	1.70	1.5	1.70	64.84	86.90
2	812	2.00	3.0	6.60	72.21	84.25
3	848	1.00	50.00	9.10	68.29	90.22
4	832	1.05	2.5	11.40	59.00	83.00
5	834	1.75	2.5	16.20	76.92	81.90
6	850	1.72	50.00	22.70	75.95	82.54

cals formed in the pyrolysis reaction. If the polymerization inhibitor is HF , it will have already been removed from the TFE/CO_2 mixture in the HFP distillation step.

If desired, the carbon dioxide can be separated from the TFE by passing this mixture through a conventional aqueous caustic scrubber. Both the HCl and carbon dioxide can be separated from the TFE in the pyrolyzate by aqueous caustic scrubbing, if the TFE is desired for some purpose other than recycle, e.g., monomer for subsequent polymerization to valuable polymers and copolymers.

The HFP can be separated by distillation from the higher-boiling pyrolysis products. The HFP is useful in the same manner as HFP synthesized by other techniques heretofore to make known copolymers, e.g., with TFE , or chemicals such as HFP epoxide.

The process is normally conducted on a continuous basis, i.e., continuously passing the feed mixture through the reaction zone, followed by continuous separation, scrubbing and recycling.

Specific embodiments of the process of the present invention are as follows: these embodiments are intended as examples of the present invention and not as a limitation on the scope thereof. In these examples, parts and percents are by weight unless otherwise indicated. Yield to HFP is calculated on the basis that the cyclic dimer of TFE is counted as recovered TFE . This cyclic dimer can be recovered as a valuable fluorocarbon chemical, or it can be pyrolyzed to HFP as is disclosed in U.S. Pat. No. 3,306,940 to Halliwell.

EXAMPLES 1 to 6

A series of pyrolysis experiments was conducted using the following equipment and procedure: The pyrolysis furnace consisted of a tube of Inconel metal (nickel-chromium-iron alloy with small amounts of silicon); the tube had a diameter of 0.635 cm. and heating length of about 30.5 cm. to give a volume of the heated zone of about 5 cc. The tube was heated by a 2.54 cm. diameter tubular furnace positioned about the heated length of the Inconel tube. The temperature of the tube was measured using a chromel-alumel thermocouple attached to the outside of the tube near the center of the heated zone. TFE and carbon dioxide were fed as

25 These results show high yields to HFP at various $\text{TFE}/\text{carbon dioxide}$ feed ratios and other variations in process conditions.

EXAMPLES 7 to 10

30 These experiments were conducted in a larger pyrolysis furnace in which the Inconel tube was 1.78 cm. in diameter and 487 cm. long, with the thermocouple being installed inside the tube and near its exit end, with the procedure including pressure being essentially the same as in Examples 1 to 6. The following pyrolysis conditions were used and results were obtained.

Exam- ple	Temp. °C.	Contact time-sec.	TFE/CO_2 wt.ratio	TFE Conversion %	Yield to HFP %
7	819	1.0	1.54	20.8	90.7
8	835	2.0	1.31	51.0	87.5
9	790	2.0	1.31	34.4	87.9
10	796	1.0	1.54	28.8	89.6

50 These experiments were operated for 22 hours with no problem in temperature control being encountered, indicating that disproportionation was not occurring.

EXAMPLES 11 to 12

The co-distillation of TFE , CO_2 , and HCl and separation from HFP and the higher boiling fluorocarbon pyrolysis products can be done as follows: The pyrolyzate, for example that obtained from the run illustrated by Example 8, is compressed and fractionally distilled to recover an overhead mixture consisting of unreacted TFE , CO_2 , and HCl boiling at -22°C. at a pressure of 14.7 kg/cm². The desired product HFP is recovered from the tails stream of the column.

60 The recycle of carbon dioxide and unreacted TFE to the pyrolysis furnace can be done as follows: The pressure of the TFE , CO_2 , and HCl distillate of the preceding paragraph is reduced to atmospheric pressure, and the distillate is scrubbed in water to remove HCl and is dried over CaSO_4 . The composition of the resultant

TFE and CO₂ mixture is 39 percent TFE by weight and 61 percent CO₂ by weight. To 1 part of the product is added 0.41 parts of makeup TFE to give a mixture of TFE and CO₂ having a TFE/CO₂ weight ratio of 1.31. This mixture is fed to a heated Inconel tube at a rate to give the contact times and results shown in Examples 11 and 12; the contact time being defined as the volume of the reactor divided by the volumetric flow of the ambient temperature feed per second.

Exam- ple	Temp. °C.	Contact time-sec.	TFE/CO ₂ wt. ratio	TFE Conversion %	Yield to HFP wt. %
11	811	1.0	1.31	28.8	86.2
12	845	2.0	1.31	64.6	83.5

Alternatively, the feed mixture of TFE and CO₂ can be recycled to the furnace and under the conditions of Example 8.

As many apparently widely different embodiments of this invention may be made without departing from the spirit and scope thereof, it is to be understood that this invention is not limited to the specific embodiments thereof except as defined in the appended claims.

I claim:

1. In a process for pyrolyzing in a reaction zone a feed mixture of tetrafluoroethylene (TFE) at a temperature between 700° and 900°C. to convert at least 20

percent of the TFE to hexafluoropropylene (HFP), with injection of a material selected from the class of HCl or HF into the pyrolysis mixture to prevent polymerization of unconverted TFE, followed by cooling and separation of HFP, and recycling of unconverted TFE with makeup TFE; the improvement which comprises diluting the feed to the pyrolysis with CO₂ at a TFE:CO₂ weight ratio of 1:1 to 25:1 so the TFE partial pressure is at least 360 mm Hg absolute and the total pressure is 0.75 to 2.0 atmospheres absolute.

2. The process of claim 1 wherein HCl or HF is separated from the cooled product mixture by water scrubbing, the HFP is separated from the TFE-CO₂ mixture by distillation, and the TFE-CO₂ mixture remaining is recycled.

3. The process of claim 1 wherein HCl or HF and CO₂ is separated from the cooled product mixture by aqueous caustic scrubbing, the HFP is separated from the TFE by distillation, and the TFE remaining is recycled.

4. The process of claim 1 wherein at least 40 percent by weight of said feed mixture is carbon dioxide.

5. The process of claim 1 wherein the pyrolysis is conducted to a conversion of tetrafluoroethylene of 20 to 80 percent by weight.

6. The process of claim 5 wherein the pyrolysis is conducted to a yield of hexafluoropropylene of at least 80 percent by weight.
